UNITED STATES PATENT OFFICE.

ARTHUR G. SARGENT, OF EAST TILTON, ASSIGNOR OF ONE-HALF TO THE
LACONIA CAR COMPANY, OF LACONIA, NEW HAMPSHIRE.

THERMOSTAT.

SPECIFICATION forming part of Letters Patent No. 441,855, dated December 2, 1890.

Application filed April 14, 1890. Serial No. 347,764. (No model.)

To all whom it may concern:

Be it known that I, ARTHUR G. SARGENT, of East Tilton, in the county of Belknap and State of New Hampshire, have invented certain new and useful Improvements in Thermostats, of which the following is a specification.

This invention relates to thermostats in which the movements that open and close a damper-ventilator or other heat-regulating device are caused by the expansion and contraction of a suitable liquid; and it has for its object to provide a thermostat of this class having a very large area of heat absorbing and radiating surface in proportion to the quantity of liquid employed, and in which the parts can be readily assembled and separated.

To this end the invention consists in the improvements which I will now proceed to describe.

In the accompanying drawings, forming a part of this specification, Figure 1 represents a side elevation of a thermostat embodying my invention. Fig. 2 represents an end view of the same. Fig. 3 represents a side view of one of the expansion members or receptacles. Fig. 4 represents a section on line 4-4, Fig. 3.

The same letters and numerals of reference indicate the same parts in all the figures.

In carrying out my invention I provide a suitable frame or holder, which may be of desirable construction, and is here shown as composed of end pieces *a a'*, and parallel side bars *b b* rigidly connecting said end pieces. Said frame may be supported in the room or compartment in which the thermostat is to work by bolts passing through holes *c c* in the end pieces *a a'*, or otherwise.

ddd represent the expansion members, each of which is a liquid-holding receptacle having substantially parallel side pieces made of thin and flexible sheet metal, preferably copper. The side pieces of each receptacle are separated by a space which is very thin in proportion to the area of the side pieces, so that each receptacle is adapted to hold a body of liquid, which has large surface areas and but little thickness, so that it can quickly absorb and radiate heat.

In practice I prefer to make each receptacle in three parts—viz., a rigid metallic marginal frame 5 of annular form having shoulders 6 on its inner periphery, and two disks 7 7 of thin sheet metal soldered at their margins 55 to said shoulders and constituting the flexible side pieces of the receptacle.

To the outer surfaces of the side pieces 7 7 at the centers thereof are soldered or otherwise securely attached outwardly-projecting 60 studs 8 8, the same being preferably provided with flanges 9 at their inner ends to give a sufficiently-extended bearing on the flexible metal of the side pieces.

i represents sleeves or ferrules, which are 65 interposed between the receptacles, and are formed to receive the stud 8, as shown in Fig. 1, each sleeve receiving two studs and bearing at one end on the flange of one stud and at the other end on the flange of the other 70 stud, so that the sleeves constitute rigid connections between the receptacles or members, whereby motion is transmitted from each member to the next throughout the series, as presently described. The sleeves, when engaged with the studs 8, as shown, connect the 75 expansion members or receptacles in a series, and prevent the edgewise displacement of said members when the ends of the series are engaged with the supports next described.

o represents a stud rigidly attached to the frame-piece *a'* and having its inner end formed to enter the sleeve or ferrule *i* at one end of the series of members, said stud constituting a fixed support for that end of the 85 series.

p represents a stud adapted to slide in a guiding-orifice in the other frame-piece *a*, and having its inner end formed to engage the sleeve or ferrule 8 at the other end of the 90 series of members. To the sliding stud *p* is affixed a cross-bar *q*, which is adapted to slide on the rods or bars *b b* of the supporting-frame. A spring *r* is interposed between the fixed cross-bar *a* of the frame and the 95 sliding cross-bar *q*, said spring being arranged to press the stud *p* toward the fixed stud *o*. It will be seen that the sliding stud *p* constitutes a yielding support for the end of the series of members opposite the end supported 100

by the fixed stud o , so that all the members are movable from the fixed stud and toward the sliding stud.

The receptacles or members d are filled with 5 alcohol or some other suitable liquid, or, if preferred, with a semi-liquid material, each member containing, as already stated, a thin body or sheet of the material spread out so as to present large areas for the absorption and 10 radiation of heat. The expansion of the inclosed material by an increase of temperature causes the flexible sides of the receptacle to bulge outwardly, the thickness of each receptacle being thus increased, so that all the 15 members are displaced or moved sidewise toward the yielding stud, the latter being moved outwardly against the force of the spring r a distance which is determined by the expansion of each member multiplied by the number 20 of members. When the temperature is reduced, the inclosed material in the receptacles contracts and the spring r forces the stud inwardly as far as the contraction of the members will permit. The sliding stud or 25 support p is pivoted at its outer end to levers, one end of which is connected at u with a fixed support t , and the other end at v with a rod extending to a ventilator or other suitable heat-regulating device, which is operated 30 by the movements of the lever s and sliding stud p .

It will be seen that the studs 8 on the receptacles and the sleeves i , in which said studs are removably inserted, not only co-operate in 35 holding the receptacles in a connected series, but also permit the receptacles to be readily

assembled or put together to form the series without screws, bolts, or other like fastening devices, and as readily separated in case repair of one or more of the receptacles becomes necessary, the receptacles with their lugs and the sleeves receiving the lugs being held in their operative relation to each other by the spring-pressed support p and the rigid support o .

I claim—

In a thermostat, the combination of a supporting-frame, a fixed support, as o , secured to one end of said frame, a spring-pressed movable support, as p , adapted to slide in a 40 guide in the other end of the frame, a series of receptacles interposed between the fixed support o and the sliding support p , each receptacle having flexible sides and rigid lugs or studs projecting outwardly from said sides, 45 the series of sleeves or ferrules in which said lugs are removably inserted, said sleeves and lugs co-operating in holding the receptacles in a connected series, one end of which is supported by the fixed support o and the other 50 end by the sliding support p , and a valve or damper controlling lever engaged with the sliding support, as set forth.

In testimony whereof I have signed my name to this specification, in the presence of 65 two subscribing witnesses, this 8th day of April, A. D. 1890.

ARTHUR G. SARGENT.
